UNITED STATES PATENT OFFICE.

ZEALIE VAN RAALTE, OF NEW YORK, N. Y.

DESIGN FOR VEILING.

50,593.

Specification for Design.

Patented Apr. 10, 1917

Application filed January 26, 1917. Serial No. 144,785. Term of patent 3½ years.

To all whom it may concern:

Be it known that I, ZEALIE VAN RAALTE, a citizen of the United States, residing in the city, county, and State of New York, have invented a new, original, and ornamental Design for Veilings, of which the following is a specification, reference being had to the accompanying drawing, forming part thereof.

The figure shown is a plan view of a portion of veiling, showing my new design.

I claim:

The ornamental design for veiling, as shown.

Z. VAN RAALTE.
